UNITED STATES PATENT OFFICE.

LOUISE L. COLEMAN, OF WHITE PLAINS, NEW YORK.

DESIGN FOR A DOLL.

Application filed September 7, 1923. Serial No. 7,157. Term of patent 3½ years.

To all whom it may concern:

Be it known that I, LOUISE L. COLEMAN, a citizen of the United States, and a resident of White Plains, county of Westchester, and State of New York, have invented a new, original, and ornamental Design for Doll, of which the following is a specification, reference being had to the accompanying drawing, forming a part hereof, in which the figure shown is a front perspective elevation of a doll, showing my new design.

I claim:

The ornamental design for a doll, as shown.

LOUISE L. COLEMAN.
